UNITED STATES PATENT OFFICE

153,932

DESIGN FOR A CHAIR

John H. Fraser, Marietta, Ohio

Application July 16, 1947, Serial No. 140,328

Term of patent 14 years

(Cl. D15—1)

To all whom it may concern:

Be it known that I, John H. Fraser, a citizen of the United States, residing at R. D. 1, Marietta, in the county of Washington and State of Ohio, have invented a new, original, and ornamental Design for Chair, of which the following is a specification, reference being had to the accompanying drawings, forming part thereof.

Figs. 1 and 2 are front and rear perspective views, respectively, showing my new design for a chair.

I claim:

The ornamental design for a chair, as shown.
JOHN H. FRASER.
